CLAIM

The ornamental design for a footwear tread, as shown and described.

DESCRIPTION

FIG. 1 is a perspective view of the footwear tread in accordance with a first embodiment of the ornamental design;

FIG. 2 is a top elevational view of the footwear tread of the first embodiment;

FIG. 3 is a left side elevational view of the footwear tread of the first embodiment;

FIG. 4 is a right side elevational view of the footwear tread of the first embodiment;

FIG. 5 is a rear elevational view of the footwear tread of the first embodiment;

FIG. 6 is a front elevational view of the footwear tread of the first embodiment;

FIG. 7 is a perspective view of the footwear tread in accordance with a second embodiment of the ornamental design;

FIG. 8 is a top elevational view of the footwear tread of the second embodiment;

FIG. 9 is a left side elevational view of the footwear tread of the second embodiment;

FIG. 10 is a right side elevational view of the footwear tread of the second embodiment;

FIG. 11 is a rear elevational view of the footwear tread of the second embodiment; and,

FIG. 12 is a front elevational view of the footwear tread of the second embodiment.

Broken lines are environmental only and form no part of the claimed design. Broken lines adjacent shaded areas of the design represent the bounds of the claimed design and are not themselves a part of the claimed design.
